UNITED STATES PATENT OFFICE

PAUL NAWIASKY AND LUDWIG EIFFLAENDER, OF LUDWIGSHAFEN-ON-THE-RHINE, GERMANY, ASSIGNEES TO GENERAL ANILINE WORKS, INC., OF NEW YORK, N. Y., A CORPORATION OF DELAWARE

PRODUCTION OF ANTHRAQUINONE AZINES

No Drawing. Application filed December 11, 1930, Serial No. 501,745, and in Germany October 8, 1926.

The present invention relates to improvements in the production of N-dihydro-1.2.1'.2'-anthraquinoneazines.

This application is a continuation-in-part of my copending application Ser. No. 229,258 for improvements in the production of N-dihydro-1.2.1'.2'-anthraquinoneazines, filed October 27, 1927.

It is known that the valuable blue dyestuff N-dihydro-1.2.1'.2'-anthraquinoneazine can be obtained by the action of fused caustic alkali on 2-aminoanthraquinone, with or without the addition of oxidizing agents, the melt being poured into water and oxidized with air. In order to improve the yield, it has also been proposed to add to the melt salts of low fatty acids, such for example as potassium formate, potassium acetate, and the like, in the presence, if required, of an inert diluent, or to add alcoholates or phenolates, such as sodium butylate, sodium phenolate, and the like.

We have now found that still better yields of the said dyestuff or of its derivatives when starting from substituted 2-amino-anthraquinone, may be obtained if salts of low fatty acids, namely of formic, acetic or propionic acid, are added to the caustic alkali melt in conjunction with salts of fatty acids containing at least 4 carbon atoms. Salts of the latter kind comprise, for example, alkali metal salts of butyric acid (normal or iso-), valeric acid, stearic and palmitic acid.

According to the present invention the caustic alkali melt may be carried out with an addition of oxidizing agents or also in the absence of such agents, and preferably with fused caustic potash-soda.

The following examples will further illustrate the nature of the said invention, but the invention is not limited thereto. The parts are by weight.

Example 1

15 parts of dehydrated sodium acetate are stirred into 200 parts of a mixture, in molecular proportions, of caustic potash and soda at a temperature of about 200° C., 20 parts of soap being then added. Thereupon 75 parts of β -aminoanthraquinone are introduced, and the mixture is stirred at a tem-

perature of from 200° to 210° C. until the production of the dyestuff ceases to increase. The separation of the dyestuff is effected in the usual manner.

55

Example 2

75 parts of dehydrated sodium acetate are introduced into a melt of 2,000 parts of caustic potash-soda at a temperature of 250° C., 45 parts of potassium isobutyrate being 60 then added and the mixture stirred until uniform distribution has taken place. The mixture is then cooled down to a temperature of 210° C. and 500 parts of β -aminoanthraquinone are introduced in such a way that the temperature does not rise above 230° C. The whole mixture is maintained at a temperature of 225° C. until the production of dyestuff ceases to increase and β -aminoanthraquinone 65 can no longer be detected. The melt is then treated in the usual way.

70

The potassium isobutyrate may be replaced by potassium butyrate which gives an equally good result.

75

What we claim is:—

1. The process of producing N-dihydro-1.2.2'.1'-anthraquinoneazines, which comprises subjecting a 2-aminoanthraquinone to the action of a caustic alkali melt in the presence of a salt of a low fatty acid in conjunction with a salt of a fatty acid containing at least 5 carbon atoms.

80

2. The process of producing N-dihydro-1.2.2'.1'-anthraquinoneazines, which comprises subjecting a 2-aminoanthraquinone to the action of a caustic potash-soda melt in the presence of a salt of a low fatty acid in conjunction with a salt of a fatty acid containing at least 5 carbon atoms.

85

3. The process of producing N-dihydro-1.2.2'.1'-anthraquinoneazine, which comprises subjecting a 2-aminoanthraquinone to the action of a caustic alkali melt in the presence of a salt of a low fatty acid in conjunction with an alkali metal salt of a valeric acid.

90

In testimony whereof we have hereunto set our hands.

PAUL NAWIASKY.
LUDWIG EIFFLAENDER.
